G. T. MUDD,
CHILD'S SEAT FOR BARBERS' CHAIRS,
APPLICATION FILED SEPT. 23, 1920.

Patented Mar. 8, 1921.

UNITED STATES PATENT OFFICE.

GEORGE T. MUDD, OF BARDSTOWN, KENTUCKY.

CHILD'S SEAT FOR BARBERS' CHAIRS.

1,370,986.

Specification of Letters Patent. Patented Mar. 8, 1921.

Application filed September 23, 1920. Serial No. 412,112.

To all whom it may concern:

Be it known that I, GEORGE T. MUDD, a citizen of the United States, residing at Bardstown, in the county of Nelson and 5 State of Kentucky, have invented certain new and useful Improvements in Children's Seats for Barbers' Chairs, of which the following is a specification.

My invention relates to a child's seat attachment for barbers' chairs and one of the 10 objects of the invention is to provide a device of this character which will be simple in construction, easy to operate and which when not in use may be folded up in back of 15 the main chair to which it is attached.

With this general object in view my invention consists of certain novel and peculiar features of construction and combination of parts as hereinafter described and 20 claimed; and in order that it may be fully understood, reference is to be had to the accompanying drawing in which:

Figure 1 is an elevation of a barber's chair showing the child's seat in position for use 25 and showing in dotted lines, the seat folded back and out of use.

Fig. 2— is a detached front elevation of the child's seat.

Fig. 3— is a fragmentary section showing 30 the stop-hinge construction which permits folding of the arms.

In the drawings, I have illustrated a conventional barber's chair provided with a seat, 1, back 2, and head rest 3. Rigidly 35 secured to the top of the chair back are a pair of lugs 4, which provide a portion of the means for pivotally and foldably securing the child's seat to the chair. The numeral 5, designates a pair of links of sub- 40 stantially the same length as the thickness or depth of the chair back, the said links being pivotally secured to the aforesaid lugs. Pivotally secured to the links 5, are a pair of back rods 6, which may be given a suitable 45 finish such as a coat of nickel plating. To the lower end of the said rods, seat supporting members 10, are pivotally connected by means of stop hinges 11. Secured to the 50 said seat carrying members 10, is a suitable cushioned seat 7. Pivotally connected to the seat 7, on each side are arm rests 9, supported by the two standards 12, the said

standards being foldably connected to the seat by means of stop hinges 13.

The operation of my invention is as follows, when it is desired to use the seat to place a child in a convenient position for the barber to cut its hair, the seat is rotated from the folded inoperative position in rear of the back, as shown in dotted lines in the drawing, to the open position as shown in full lines. The link 5, then rests on top of and the rods 6, against the chair back 2. The seat 7, is held in suitable open position by means of the stop hinges 11 and the arm 65 rests are turned up and held in position for the child's use, through the medium of the stop hinges 13.

When the child's chair is no longer desired for use the arm rests 9, are folded down 70 on the seat as shown in Fig. 3, the seat 7, is folded up against the chair back 2, and the child's chair thus folded is rotated rearwardly through approximately 360° to a position in the rear of the main chair back. 75 In this folded position, the top side of the child's seat is facing outwardly, thus making a neater appearance than if the bottom side was exposed to view.

From the above description it will be 80 apparent that my invention possesses the advantages of being constructed of a few parts which are easily produced and assembled and will not readily get out of order. When the chair is not in use, it may be compactly 85 folded out of position and still be conveniently located for ready use.

While I have illustrated and described the preferred form of my invention, it will be understood that I reserve the right to all 90 changes falling within the appended claims.

Therefore what I claim as new and desire to secure by Letters Patent is:

1. A device of the character described, an auxiliary seat member, an auxiliary back 95 member to which the seat member is rotatably connected, a chair back, means for rotatably connecting the said back member to the top of the chair back, the said seat member adapted to be folded up against the 100 back member and the said members, while in nested position, rotated to inoperative folded position in the rear of the main chair back.

2. A device of the character described, an auxiliary seat member, an auxiliary back member to which the seat member is rotatably connected, a chair back, links pivotally secured to the top of the chair back and to the said back member, the said seat member adapted to be folded up against the back

member, and the said members, while in nested position, rotated to inoperative folded position in the rear of the main chair back.

In testimony whereof I hereby affix my signature.

GEORGE T. MUDD.
